(57) **CLAIM**

The ornamental design for an air conditioner, as shown and described.

DESCRIPTION

1. Air conditioner
- 1.1 : Perspective
- 1.2 : Perspective
- 1.3 : Front
- 1.4 : Back
- 1.5 : Left
- 1.6 : Right
- 1.7 : Top
- 1.8 : Bottom

FIG. 1.1 to FIG. 1.8 show an air conditioner according to the present design.

1 Claim, 8 Drawing Sheets(56)
